UNITED STATES PATENT OFFICE.

ALFRED HINZPETER, OF MUNICH, GERMANY.

DEVICE FOR CALLING CABS, PORTERS, AND THE LIKE BY TELEPHONE.

1,084,012.

Specification of Letters Patent. Patented Jan. 13, 1914.

Application filed August 12, 1912. Serial No. 714,663.

To all whom it may concern:

Be it known that I, ALFRED HINZPETER, a subject of the Emperor of Germany, and residing at Munich, Bavaria, Germany, have 5 invented certain new and useful Improvements in Devices for Calling Cabs, Porters, and the like by Telephone, of which the following is a specification.

The object proper of my invention is to 10 call away such a vehicle or person from the place where it or he has its or his usual daily stand, or from the nearest of such stands respectively, and I attain this object, generally, by providing at or near such stand 15 or stands call signals or call apparatus, preferably telephone stations, which are connected with the telephone exchange office and registered under a special mark in the telephone book, said signals or apparatus 20 or stations being so constructed, that they are automatically locked for a certain time when a call has been made, and they remain locked until that call has been responded to, that is to say at the longest until the expiration 25 of that certain time, after which the general connection with the line is again established. This general idea may be carried into practice in a variety of ways and with the employment of apparatus of different constructions. There may be used, 30 for instance, telephone apparatus of a kind in which, after a call has been made, only one reply can be given, and such apparatus may be of the "coin-free" type, there being, 35 however, the difference with respect to other coin-free apparatus that the contrivance operated by the coin does not establish the connection for calling but that for replying. The apparatus may also be provided 40 with a means indicating to caller after some time that no one is present at the stand who can answer. Arrangements of such a kind are suited particularly for places or stands with much traffic, where the apparatus is 45 used exclusively for calling cabs or porters and the like, and no other persons want to use the telephone apparatus for their private conversations. At places, however, where such is the case, as at places with but small 50 demand for cabs, etc., I intend to make use of a coin-free apparatus having two slots, of which one is intended for the person replying to a call and the other for a person wishing to employ the apparatus for a conversation, one of the two slots being temporarily automatically locked from the other when a coin is dropped into the latter. On

the other hand, instead of combining two apparatus into one, two distinct apparatus may be used coöperating in the manner just 60 stated. In either case the slot intended for the general use is locked either until the call has been responded to, or until a certain predetermined time has elapsed. All these different forms of construction of such apparatus are shown in the accompanying drawings and all possess the characteristic feature that an electromagnet is inserted into the call circuit, this electromagnet being excited on a call, preparing the apparatus for 70 the response, and locking the slot or the second slot (if there is such a one) so that no general conversation can take place for some time, as already explained.

The Figures 1-5 show two forms of construction of the kind in which but one coin-free device is provided, these apparatus being intended merely for calling cabs, etc., that is to say, they are not intended also for general use, viz: general conversational 80 purposes; and their construction is such that the caller is automatically informed after a certain time whether or not a cab or porter is present. There is this difference between the two forms of construction in question 85 that in the first case all the essential parts, i. e. those for the general purpose of the telephone apparatus and those for the special purpose of the new arrangement and combination of parts, are combined in the 90 casing of a normal telephone apparatus, whereas in the other case the telephone apparatus is inclosed in a common casing with the novel parts, as is all more fully described hereinafter. The third form of construction shown in Figs. 6-8 concerns an apparatus, in which an existing coin-free telephone apparatus is combined with a special apparatus for calling cabs, etc., as it forms 95 the subject matter of this invention.

In order to make my invention more clear, I now refer more particularly to the before mentioned drawings, in which similar letters denote similar parts throughout the several views and in which:

Fig. 1 is a vertical section through the first form of construction. Fig. 2 shows various details which are fully described in the detailed description. Fig. 3 is a vertical section through the second form of construction, the plane of the section being in an angle of ninety (90) degrees with respect to the plane of the section of Fig. 1. Fig. 4 is a section taken at right angles to Fig.

3 (thus corresponding in so far to Fig. 1) the lower portion of the figure being broken off; Fig. 5 is a horizontal section through the lower portion of Fig. 4; Fig. 6 is a front view of the third form of construction; Fig. 7 is a vertical section through the same; and Fig. 8 shows a number of detail parts, which are all fully described hereinafter.

The apparatus shown in Figs. 1 and 2 comprises a bell or lamp 1, receiver 2, microphone 3, circuit closing and time signal clock 4, magnetic locking device 5, 6, acting on said clock, time signal bell 7, coin chute 8, the requisite switch mechanism, and if necessary illuminating apparatus 9. The hook-switch 10 acts only after a conversation, when the receiver 2 is hung up, and thereby connects the microphone circuit to the magnet circuit of the apparatus 4, and the circuit of the illuminating apparatus to the signal circuit. The reversal of these connections is effected by swinging the spindle 11, on which there is a handle 13 outside the casing 12, and a ratchet wheel 14 inside the casing. The latter acts at each quarter revolution on a switch lever 15, which moves over the respective contacts 16, 17, 18, 19. In order that the return movement is dependent on hanging up the receiver the switch 10 is connected to a rod 20 which automatically engages a pin 22 on the lever 15 when the receiver is hung up, and moves the lever back. The rod 20 is guided by a pin 90 and a spring 91, so that after moving the switch lever it recedes from the pin 22 before the hook-switch has completed its downward movement. The switch 10 consequently does not influence the switch 15 when the receiver is taken down, and this arrangement also makes it possible to actuate the switch lever from the spindle 11 before or after taking down the receiver. In order that the movement of the lever 15 can only take place after insertion of a coin, the spindle 11 carries a ratchet wheel 23 coacting with a double armed locking lever 24 which has a tooth 25, and the end 26 of which extends into the coin chute 8, so that an inserted coin 27 acts on the locking lever and releases the spindle.

The coin aperture is normally closed by a bell crank 29, which is moved to free the aperture when a call is signaled, the movement being controlled by means of a lever 30 connected to the clock 4. The lever 30 has a nose 31 resting on the bell crank 29, and a hook 32 engaged with a pin 33 on the clock 4. The latter comprises a spring motor 34 (Fig. 2) which actuates a spindle 35, and a contact disk 36 which is provided with a weight 47 and is loose on the spindle 35 and can be engaged with the said spindle by gears 37, 38, 39, 40. Rotation of the contact disk is normally prevented by the

lever 5, which is adapted to engage notches 50, of which there are two. The gear wheel 37 is fixed to the disk, and the gear wheel 40 is fixed to the spindle 35. The wheels 38 and 39 are fixed to a spindle 41 supported by arms 42 which project from a shaft 43, the latter being connected by a link 44 to a rod 45. A cam 46 fixed to the spindle 11 normally holds the rod 45 raised, whereby the wheels 38, 39 are engaged with the wheels 37, 40. On rotation of the spindle 11, consequent upon movement of the switch lever 15, the rod 45 is lowered until again lifted by the next ridge of the cam. While the rod is lowered the wheels 38, 39 are disengaged, so that the disk is uncoupled from the clock and can move independently. At the same time the clockwork is locked by a lever 48, which projects from the shaft 43, but extends around the opposite side of the disk. A tooth 49 on this lever engages the wheel 40. When the disk 36 has been disengaged from the lever 5, as will be described hereinafter, and has also been disengaged from the clockwork 34, the weight 90 rotates it to a normal position in which the notches 50 are diametrically and vertically opposite each other. The greatest movement which the disk 36 can perform for a call is half a revolution. Release of the lever 5, when a call takes place, is effected by the current passing through the electromagnet 6, so that the armature, which is fixed to the lever 5, is temporarily attracted. On the disk 36 there are two conductively connected contact rings 51, in contact with springs or brushes 52. The outer ring has two gaps 53, diametrically opposite each other, or is at these parts covered with insulating material. The brushes 52 are in a local circuit containing the signal bell or lamp, so that when contact is made at 18, current flows from a generator 54 through the lamp and brushes when the disk 36 rotates and removes one of the gaps 53 from the brush 52 lying thereon. This current continues while the disk is making half a revolution. Another local circuit from the generator includes contact 19 and lamp 9, a switch 55 being provided to render it inoperative when not required, as in the day time. The purpose of the lamp 9 is to enable the person at the receiver to write down a message. The signaling circuit *x* from the exchange, enters at 56, passes over 16 to the magnet 6, and then passes out, as indicated at *y*. The talking circuit is traced from *x* over contact 17 to the receiver 2 and microphone 3, and thence to *y*. A third circuit, for microphonically transmitting the signal, is traced from *x* over a normally open contact 57 and over a normally closed contact 87, 88 to the microphone 3, and thence to *y*. One part of the contact device 87, 88 rests on one of the arms 130

42, or on the arm 48, so that the contact is broken when the contact disk 36 is disconnected from the clockwork. If nobody answers the call, a mechanically or electrically actuated bell 7 transmits a signal through the microphone to the caller after a certain period. For this purpose the contact 57 in the last mentioned circuit is closed by one of the pins 33, and at the same time 10 the bell is struck. The bell may be mounted on an elastic arm 58, and be vibrated by arms 59 connected to the disk 36.

The action of the apparatus is as follows: The call signal current energizes magnet 6 and releases lever 5. The clockwork 34 then rotates the disk 36, whereby the coin chute is opened, and the local circuit of lamp 1 is closed by the springs 52 while the disk 36 is making half a revolution. The lamp indicates to the waiting cabman or messenger that a call has been given. He inserts a coin, whereby the spindle 11 is released for one-quarter revolution. The receiver is then taken down, and spindle 11 is rotated, 25 whereupon the message can be received, the switch lever 15 having been actuated by the spindle 11 to break the call signal circuit and connect to the microphone circuit. Before completion of the quarter revolution 30 of the spindle 11 the disk 36 is disconnected from the clockwork, and the latter is stopped, the weight 47 causing the disk to complete its half revolution, whereupon it is locked again by the lever 5. Prior to this 35 contact is temporarily made at 57, by one of the pins 33, wiping the longer contact spring 56, but this has no effect in this case, contact being broken at 87, 88 by the movement of the arms 42 and 48 in releasing the disk locking the clock. Contact at 87, 88 is not 40 re-made until at completion of the quarter revolution of the spindle 11 the cam 46 again couples the contact disk 36 with the clockwork 34 and the latter is released from the lever 48. When this takes place the coin chute is again closed, so that all the parts 45 except the lever 15, are ready for the next call. The lever 15 is restored to normal position by the act of hanging up the receiver.

In order to furnish a receipt for the coin, a paper reel 60 is provided, from which a strip of paper is fed outward by rollers 61, 62 when the handle 13 is turned. The roller 61 is fixed to the spindle 11 and has four (4) 50 abutments 63, whereby, on completion of a quarter revolution, a cutter is actuated, to cut a receipt ticket from the paper strip. The cutter comprises a knife 65 arranged on or between two arms 66, 67 which are pivoted at 64 and lie in the path of the abutments 63.

If the call remains unanswered, the contact disk 36 completes its half revolution 55 under the influence of the clockwork.

Shortly before the end of this half revolution contact is broken at 56 by one of the pins 33, and closed at 57. Inasmuch as contact is in this case not broken at 87, 88, the microphone circuit is closed for transmitting the signal, as described. 70

In the construction shown in Figs. 3 to 5 an ordinary telephone instrument 68, with its casing, is placed in a casing 69, whereof the door 70, which is in the form of a box, 75 normally prevents access to the instrument, but can be opened by means of a key after insertion of a coin. The door 70 is locked by means of a bolt 71 engaged with a pin 86, and by an auxiliary bolt 74. The bolt 71 has a lug 72, which covers the coin apertures, and is connectible to a switch lever 73, by which electric connection can be transferred from the call signal circuit to the night lamp circuit. Transference of the electric 80 connection from the call signal circuit to the talking circuit is effected in known manner by the hook-switch 10, after removal of the receiver. The bolt 74 is normally locked by a double armed lever 24 and can only 85 be retracted after insertion of a coin. The lever 24 extends through a slot into the coin chute 8, and is disengaged from the notch 75 in the bolt 74 by the coin so that the bolt 74 can be retracted by means of a key. In 90 the course of its retraction the bolt 74 moves the lever 24 and is again locked by the same, at the end of its movement, the lever 24 being restored to its normal position by an abutment 76, so that it engages a notch 77 95 in the bolt and is held therein by a bolt 78 which, when the door is opened, is pushed over the lever 24 by a spring 79. When the door is closed again an abutment 80 (Fig. 5) pushes the bolt 78 back. 100

For giving receipts, there is a paper reel 60, with feed rollers 61, 62 and a cutter 65, 63 actuated by abutments 63 on the roller 61. The latter is actuated by a ratchet wheel 81, operated by a ratchet 83 which is pivoted at 82 to the bolt 74 and is actuated when the door is unlocked. 105

All the parts so far described, except the switch lever 15 and the contacts 18 and 19 for the call circuit and the night lamp respectively, are inside the box-like door 70. Above the same the casing 69 contains the circuit closing the signaling clock, which in this case also comprises a contact disk 36, connectible by gears 37, 38, 39, 40 to the clockwork 34, and normally locked by an electromagnetic device 5, 6. The main difference lies essentially in the fact that the meshing and unmeshing of the gears 38, 39, and the actuation of the escapement 48, 49, 115 120 125 are not performed by a cam but by the movement of the door 70, the lever arm 44 fixed to the shaft 43 resting on the inner top edge of the door. The clock also differs from that previously described, in that, for the purpose 130

of giving the "no answer" signal, it does not temporarily close a microphone circuit which is independent of the receiver switch, but actuates the receiver switch for closing the 5 microphone circuit, when the "no answer" signal is given. For this purpose the contact disk 36 has two arms 84, each adapted to engage a rod 85 connected to the receiver switch 10, so that the latter is lifted before 10 completion of half a revolution of the disk 36 under the influence of the clock. The bell 7 is in this case preferably so arranged that it is actuated by one of the arms 84 shortly after the latter begins to lift the switch 10, 15 said arms having offset portions whose path of revolution causes them to contact with the bell, the actuation of the bell ceasing before the arm releases the switch 10.

In regard to the circuits it need only be 20 mentioned that the electromagnet 6 must be in the call circuit of the telephone 68. For the signaling lamp and the night lamp there are circuits similar to those previously described, as diagrammatically illustrated in 25 Fig. 4.

The door 70 is opened by inserting a key 89, and giving it half a turn, whereby the bolt 71 is retracted and enables a coin to be inserted, so that the bolt 74 is released and 30 can be retracted by completing the revolution of the key. In locking the door, the key shoots first the bolt 74 and then the bolt 71.

Referring now to the form of construction represented in Figs. 6 and 7, in which an 35 existing coin-free telephone apparatus is combined with a special apparatus for calling cabs, porters, and the like, there is a slot 92 to be used for calling the exchange office in order to establish a connection for a conversation, and a slot 93 to be used when replying to a call for a cab and the like. Each 40 of the slots is provided with a plate indicating the special object of each of them.

Behind each slot is one leg of a forked 45 chute 94, which terminates in known manner above a switch lever 95 and a relay armature 96, by means of which the coin is re-conducted to the outside by aid of a chute 97 if it has not been possible to establish a connection, and consequently a current of a certain 50 strength has been made to pass through the relays, either from the exchange office or by the person calling. Behind the two slots is a forked locking lever 99, one of the legs 55 of which closes either the slot 92 or the slot 93. This lever is actuated, when a call is made, by means of an electromagnet inserted into the call signal line. For this purpose the forked lever has an upwardly extending 60 middle arm 100, which can be moved by a lever 101 positively connected with the axle 102 of the locking lever 5 holding the armature of the electromagnet 6 so that the lever 101 can change the position of the lever 99 65 simultaneously with releasing the time-

movement if the armature in question is attracted when a subscriber calls. The general slot 92 is then locked, for instance by the left hand leg of the lever 99, and the special slot 93, which was closed up to then is now 70 freed from the other leg of that lever. The latter remains in this position until the locking-lever 5 has entered the next notch 50 of the time-movement 4, or of the contact disk 36 respectively, that is to say, after the time-movement has made one half rotation. The locking lever may then return to its former 75 position either under its own weight or by the aid of a counterpoise or spring. The locking lever 99 may have plates 103 with 80 inscriptions indicating that this or that slot is closed, appearing behind a cut-out, window 104 or the like.

The other parts and arrangements of the device, such as for artificial illumination for 85 the evening and night hours, delivering a receipt, a permanent signal, an end signal, if the call has not been responded to, and the like, are the same as in Figs. 1 and 2, but said parts and arrangements may be replaced, if desired, by other, equivalent ones. For instance in the form of construction shown in Figs. 6 and 7, the signal lamp 1 of the apparatus shown in Figs. 1-5 is replaced by a double bell 105 of known construction. 90 This bell is inserted into the local circuit containing the source of energy 54, the contact spring 52 of the clock 4, and the contact pieces 18. The night lamp is put into another local circuit also fed from the source of electricity 54, this circuit containing the contact pieces 19 and the cut-out 55.

The clock or time-movement is practically the same as that shown in Figs. 1 and 2, and it may also be actuated by hand by the 105 mediation of a cam disk 46; furthermore, the means for delivering a receipt, in connection with those for separating it from the strip, are practically the same.

106 is a coin catching chute, into which the 110 coin dropped into a slot is guided by the change-over lever 95 and by which that coin is conducted to a collecting receptacle 107 when the telephone connection desired has been established.

The hook switch 10 acts by the same means in the same manner, *i. e.* it switches over the microphone circuit to the magnet wire of the locking device for the time signal clock, and the illumination circuit to the signal line, provided the telephone has again been put back on the hook after a conversation. Changing over in the reverse direction is effected in this form of construction by the thrown in coin 27 which drops upon 125 the switch lever 95 and changes its position from that shown in dotted lines to that indicated in full ones.

108 and 109 are two plates attached to the 130 casing at the slots 92 and 93 and bearing in-

scriptions relative to the particular purposes of these slots. The left hand plate, for instance, may bear the words "Public telephone 5 cents", and the right hand plate 5 may bear the words: "Cab call for cabmen only."

Fig. 8 shows diagrammatically the most simple way of employing an existing coin-free telephone apparatus for calling cabs 10 and the like. There is again an electromagnet 6 in the bell circuit, the armature of that magnet being affixed to a lever 5. To the axle 102 of this lever is secured a lever 101, which ordinarily keeps open a flap or drop 15 disk 110, which is released as soon as upon a call being made the current excites the magnet causing it to attract its armature. The drop disk then becomes visible behind the slot 111 indicating thus that the apparatus is 20 just being required to order a cab or the like. There may be special conspicuous inscriptions intended chiefly for outsiders, to prevent their using the apparatus in a wrong manner. When a cab driver is at the 25 stand, he goes to the apparatus turns the drop disk into its position of rest, drops a coin into the slot, and can now answer the call, hearing where he is desired to come. Other persons having nothing to do with 30 cabs, etc., but wishing to use the apparatus for a conversation, must wait, say 1 or 2 minutes before they are allowed to replace the flap; the expiration of that time may be indicated by the exchange office through a 35 special signal.

The arrangement of the flap is preferably such that its extent of movement in both directions is limited to the indispensably requisite measure, and that on throwing the 40 flap back it is automatically locked by the lever 101, which has already returned to its former position.

What I claim as new and desire to secure by Letters Patent is:

45 1. In an apparatus for calling cabs, porters, and the like by telephone, the combination with a telephone apparatus, of time controlled means for closing said apparatus against other calls after a call has been 50 made, and means for terminating said closing action, for the purpose as described.

2. In an apparatus for calling cabs, porters, and the like by telephone, the combination with a telephone apparatus including 55 a local station, an exchange office and a connection between said exchange office and local station including a signaling circuit, of an electromagnet inserted into the signaling circuit, time control means adapted to be 60 actuated by said electromagnet and to cut out the apparatus from other calls after a

call has been made, and means for interrupting said cutting out action, for the purpose as described.

3. In an apparatus for calling cabs, porters and the like by telephone, the combination with a telephone apparatus including a local station, an exchange office and a connection between said exchange office and local station including a signaling circuit, of 65 an electromagnet connected to the signaling circuit, an armature for said electromagnet, time control means adapted to cut out the apparatus from other calls after a call has been made and adapted to be operated by 70 said armature, and means for releasing the apparatus from other calls after a call has been made and adapted to be operated by 75 said armature, and means for releasing the cutting out parts, for the purpose as described.

4. In an apparatus for calling cabs, porters and the like by telephone, the combination with a telephone apparatus, an exchange office, conversation and signaling circuits connecting the telephone and exchange office, of an electromagnet inserted into the 80 signaling circuit, a clock work adapted to be released by said electromagnet, a circuit closed by said clock work, a signal adapted to be actuated by this circuit, and means for breaking this circuit automatically, for the 85 purpose as described.

90 5. In an apparatus for calling cabs, porters and the like by telephone, the combination with a telephone apparatus, an exchange office, conversation and signaling circuits connecting the telephone and exchange office, 95 of an electromagnet inserted into the signaling circuit, a wheel work adapted to be released by said electromagnet, a circuit adapted to be closed by said wheel work, a signaling device situated in said circuit, and means 100 for interrupting this circuit after a predetermined time, for the purpose as described.

6. In an apparatus for calling cabs, porters, and the like by telephone, the combination with a telephone apparatus, an exchange office, conversation and signaling circuits connecting the telephone and exchange office, of an electromagnet inserted into the 105 signaling circuit, a wheel work adapted to be released by said electromagnet, a signaling device adapted to be connected by said wheel work with the conversation circuit of the calling subscriber, and means for stopping the said wheel work after a predetermined period, for the purpose as described. 110 115

In testimony whereof I affix my signature in presence of two witnesses.

ALFRED HINZPETER.
